UNITED STATES PATENT OFFICE.

PETER D. MILLOY, OF BUFFALO, NEW YORK, ASSIGNOR TO AUTOMATIC TROLLEY CATCHER AND CONTROLLER COMPANY, OF SYRACUSE, NEW YORK, A CORPORATION OF NEW YORK.

TROLLEY-CONTROLLER.

SPECIFICATION forming part of Letters Patent No. 698,532, dated April 29, 1902.

Application filed March 28, 1901. Serial No. 53,800. (No model.)

To all whom it may concern:

Be it known that I, PETER D. MILLOY, of Buffalo, in the county of Erie, in the State of New York, have invented new and useful Improvements in Trolley-Controllers, of which the following, taken in connection with the accompanying drawings, is a full, clear, and exact description.

My invention relates to improvements in trolley-controllers, having more particular reference to the means for preventing the upward movement of the trolley-arm when the trolley accidentally leaves the wire.

The object of this invention is to provide means connected to the trolley-arm by the trolley-operating cord for preventing upward movement of the trolley-arm when the trolley is accidentally displaced from the trolley-wire or conductor.

The further object of this invention is to provide a suitable take-up mechanism for permitting the vertical movement of the trolley-arm while passing along a conductor arranged at varying heights from the road-bed, or, in other words, to automatically take up the slack of the operating-cord for the trolley-arm.

A further object of this invention is to so support the operating mechanism for preventing the upward movement of the trolley-arm as to permit it to automatically adjust itself as the cables or cords are wound upon the drums in order that the cord for tensioning the mainspring and the operating-cord for the trolley-arm may not become entangled one with the other or displaced, and a still further object is to so construct the support as to permit ready access to the operating parts without in any way dissembling the device.

To this end the invention consists in the construction, combination, and arrangement of the parts of a trolley-arm-controlling mechanism, as hereinafter fully described, and pointed out in the claims.

Referring to the drawings, Figures 1 and 2 are side elevations of my invention viewed at right angles to each other, the lower portions being broken away for disclosing the interior

mechanism, the operating-spring being shown 50 in its operative position in Fig. 1 and as released in Fig. 2. Fig. 3 is a view, partially in perspective, of the detached operating mechanism for the trolley-arm, the spring being shown in its inoperative position, as seen in 55 Fig. 2. Figs. 4, 5, and 6 are sectional views taken, respectively, on lines A A, Fig. 2, B B, Fig. 1, and C C, Fig. 4. Figs. 7 and 8 are sectional views taken, respectively, of lines D D and E E, Fig. 2.

Similar reference characters indicate corresponding parts in all the views.

My invention consists, essentially, of an inclosing case or frame 1, a suitable take-up device 2 for the operating-cord 3 of the trolley-arm, a spring-motor 4, means for tensioning the spring-motor, and one or more catches 5 for holding the spring in its tensioned position.

The supporting case or frame 1 may be of 70 any desired form, size, or material, but preferably consists of a metallic cylinder having a removable flanged base 7 and terminating at its upper end in an enlarged head 8, the base 7 being provided with an annular flange 75 extended into the lower cylindrical end of the frame 1 and secured thereto by suitable fastening means, as screws 9, said base being arranged to be secured to the floor or platform of a car.

The upper end or head 8 of the frame 1 is provided with a guide-opening 10 for receiving the outgoing end of the operating-cord, which is attached to the trolley-arm in a manner well known and not necessary to herein 85 illustrate or describe, said upper end or head being also provided with opposite substantially flat walls, one of which is formed with an opening 11, and the other wall is provided with a circular toothed rack 12 for a purpose 90 hereinafter mentioned. The opening 11 is preferably formed of sufficient diameter to permit the insertion and withdrawal of the take-up device 2 and also other smaller mechanisms which it may be desired to insert through said 95 opening. This opening 11 is closed by a suitable cap 13, which usually consists of a circular plate or disk having one of its side

edges provided with an inwardly-projecting shoulder 14, arranged to interlock with the adjacent edge of the opening, and is preferably inserted between suitable pins 15 for preventing lateral or peripheral movement of the plate 13. I also provide said plate with a hook-shaped lug 16, which is arranged at the opposite edge of the plate and engages a suitable clamping-screw 17, movable in a threaded aperture in the adjacent portion of the frame. The wall of the frame 1, opposite the opening 11, is provided with an inwardly-projecting stud or spindle 18, having a series of ball-bearings 19 at its base, which are adapted to receive and support one end of the rotary take-up mechanism 2, the other end of said take-up mechanism being supported upon the conical bearing 19', which is formed on the inner end of a screw adjustably mounted in the circular plate or disk 11 at substantially its central point, said bearing being adjustable toward and away from the ball-bearings 19 for compensating for the wear of the bearings and also serving to reduce the friction between the rotary take-up mechanism and its bearings.

In order to permit access to the interior of the intermediate portion of the supporting frame or casing 1, I usually provide the frame with an additional opening 20, which is closed by a suitable closure 21, hinged at 22 to the frame 1, and its opposite end is held in position by a pivoted catch 23, movable into and out of engagement with the movable end of the door or closure 21.

The take-up mechanism for the operating-cord of the trolley-arm consists of a rotary drum mounted upon the bearings 19 and 19', and a spring-motor 24, arranged within said drum and having one end connected to the spindle 18 and its other end connected to the drum, whereby the drum may be rotated in one direction automatically for winding the cord upon the drum, and thereby taking up and letting out the rope or operating-cord to conform to the varied height of the trolley-arm during its travel along the conductor. The operating-cord 3 is secured at one end to the periphery of the drum 2, and its other end is attached to the trolley-arm in the usual manner.

Secured to the face of the drum 2, adjacent to the circular rack 12, is a pawl 25, which is pivoted at one end to said drum, and its other end is movable into and out of engagement with the teeth of the circular rack 12 for the purpose of holding the drum from rotary movement in the direction which unwinds the operating-cord therefrom, or, in other words, in the direction opposite to the movement transmitted thereto by the spring 24. This dog or pawl 25 is normally held out of engagement with the teeth of the circular rack 12 by a light coil-spring 27, coiled around its pivot and engaged therewith in any well-known manner, and is adapted to be moved outwardly into engagement with the teeth of

the circular rack by the centrifugal force incidental to the rapid rotation of the drum 2 by a mechanism hereinafter described.

In order to permit the insertion or removal of the spring-motor 24 within the drum 2, I preferably provide said drum with a removable cap 28, which is held in position by fastening means, as screws 29, this cap being formed with a conical bearing for the conical end of the screw 19'. The means for imparting the necessary rapid rotary movement to the drum 2 for forcing the pawl 25 into engagement with the teeth of the circular rack 12 consists of the operating-cord of the trolley-arm and incidentally of the coil-spring motor 4, having its lower end fixed from endwise movement to the base 7, being preferably swiveled thereto by a suitable bolt 29' and its upper end secured to a vertically-movable head 30, having an upright bracket 31, provided with a sheave 32, said bracket being movable vertically independently of the head 30 and is connected to pivoted arms 33, which in turn are arranged to move the catches 5 out of operative position for releasing the spring-motor 4. The sheave 32 is mounted upon or connected to the intermediate portion of the operating-cord of the trolley-arm, said cord being passed downwardly around the lower face of the sheave and then upwardly and connected to the trolley-arm, as previously stated.

The catches 5 are mounted in suitable ways formed in the head 30, are adapted to engage shoulders 34 upon the inner face of the frame 1 for holding the spring 4 in its extended or tensioned position, said catches being held in engagement with the shoulder by a spring 35, which tends to force the catches 5 simultaneously away from each other and into engagement with the shoulders 34. These catches 5 are formed with shoulders which are arranged to interlock with similar shoulders formed upon the arms 33, so that when the bracket 31 is elevated a slight distance the arms 33 are rocked upon their pivots, and the shoulders of said arms engage the similar shoulders upon the catches 5, thereby withdrawing said catches from engagement with the shoulder 34 and releasing the upper end of the spring, which returns to its normal inoperative position, as seen in Figs. 2 and 3, with considerable force. It is thus evident that as the operating-cord for the trolley-arm is tensioned at both ends and that the upper end of the spring carrying the sheave 32 is supported upon the intermediate portion of the trolley-cord said cord is instantaneously drawn downwardly with great force, thereby tensioning the spring-motor within the drum 2 and also drawing the trolley-arm downwardly. It is further apparent that by the sudden upward movement of the upper end of the cord 3 the drum 2 is rotated with considerable velocity, which moves the pawl 25 outwardly by centrifugal force into engagement with the teeth of the circular rack

2, and that as soon as the said pawl is forced into engagement with the teeth of said rack the drum ceases to rotate, and the trolley-arm is drawn downwardly with considerable force 5 and held from further upward movement.

The means for elevating and tensioning the spring-motor 4 preferably consists of an automatic take-up drum 37, a sheave 38, connected to the head 30, and an operating-cord 10 or equivalent device 39, having one end secured to the periphery of the drum 37 and its other end passed downwardly and beneath the lower face of the sheave 38 and upwardly through an aperture 40 in the frame 1 and 15 provided with a suitable handpiece 41. The take-up drum 37 is similar to the take-up mechanism 2, being somewhat smaller in diameter, and is mounted upon a spindle 42, secured to the frame 1 and extending inwardly 20 into the interior chamber of said frame, said drum being provided with a spring-motor 43, arranged within the drum and tensioned to rotate the drum in substantially the same direction as the drum 2, it being understood 25 that the axes of said drums 2 and 37 are substantially parallel. The spindle 42 extends only partially across the interior chamber of the frame 1 and is provided with suitable means, as a cotter-pin 44, for holding the 30 drum from endwise movement upon the spindle 42, said drum being also provided with a removable cap 45, similar to the cap 28 of the drum 2. The sheave 38 is mounted upon the upper end of the bracket 45, the lower end 35 of which is secured to the head 30 by suitable fastening means, as screws 46, said bracket being extended above the supporting-bracket for the sheave 32 and is formed with an opening for receiving said sheave 32 and its supporting-bracket and permitting the vertical 40 movement of the sheave 32 and its supporting-bracket 31. In order to reduce the friction incidental to the movement of the cord 39 through the opening 40 of the frame 1, I 45 preferably provide an additional sheave or pulley 47, which is mounted upon a spindle 48, carried by suitable ears 49, which form a portion of the frame 1.

In the operation of my invention, assume 50 that the spring-motor 4 is in its normal position, as seen in Figs. 2 and 3, in which instance the cord upon the drum 37 is substantially unwound, as seen particularly in Fig. 3, it being understood that the spring-motor 43 is tensioned when the operating-cord 39 is 55 in the position seen in Figs. 2 and 3. The operator then draws upwardly upon the handpiece 41, thereby elevating the free end of the spring-motor 4 until the catches 5 automatically engage the shoulders 34, whereby 60 the spring is held in its extended or tensioned position. The handpiece 41 is then released, and the drum 37 is automatically rotated by the spring 43 for taking up the slack of the 65 cord 39. During the movement of the trolley along the wire or conductor (not illustrated)

the operating-cord for the trolley-arm is slightly tensioned by the spring-motor of the drum 2, thereby taking up the slack of said operating-cord 3 and permitting the trolley-arm to move vertically to conform to the varied heights of the trolley-wire, said cord rendering through the sheave 45 under normal conditions without effecting the releasing of the upper end of the spring-motor 4, it being 70 understood that the normal movement of the operating-cord 3 through the sheave is gradual, the spring between the catches 5 being sufficiently stiff to prevent the withdrawal of the catches from the shoulders 34, except when 75 a sudden jerk or pull is imparted to the sheave 45 and its supporting-bracket 32, which, it will be noted, is connected to withdraw the catches 5 from the shoulders 34 for releasing the spring-motor 4. Should the trolley accidentally leave the wire or conductor, the sudden 80 upward movement of the trolley-arm and the operating-cord connected thereto causes the drum to be rotated a limited distance with sufficient speed to force the pawl 25 into engagement with one of the teeth of the rack 85 12. This action of the pawl instantly checks the further movement of the drum 2, and the operating-cord being tensioned at its other end by the upward tendency of the trolley-arm 90 instantly elevates the sheave 45 and its supporting-bracket for withdrawing the catches 5 from the shoulders 34, and thereby releasing the spring 4. The downward movement of the upper end of the spring 4, carried 95 by its retraction, draws the free end of the operating-cord and the trolley-arm connected thereto downwardly with great force 100 and holds the same in this position until the pawl is released by a downward pull upon the operating-cord, whereupon the drum 2 immediately takes up the slack, and the trolley may again be aligned with the wire by the operator. The spring-motor is then again tensioned by the operator in the manner previously described and the operation repeated 105 as often as the trolley accidentally leaves the wire.

It is apparent from the foregoing description that the operation of my invention is 110 entirely automatic; that immediately upon the accidental displacement of the trolley from the trolley-wire the trolley-arm is automatically drawn downwardly in a plane beneath the trolley-wire, thereby obviating all 115 liability of damage to the overhead wires or any part of the trolley mechanism, and also relieving the liability of short circuits or any other dangers incidental to the displacement of the trolley.

The operation of my invention will now be readily understood upon reference to the foregoing description and the accompanying drawings, and it will be noted that some change may be made in the detail construction and arrangement of the parts of my invention without departing from the spirit 125 130

thereof. Therefore I do not limit myself to the construction and combination as shown and described.

Having thus fully described my invention, 5 what I claim, and desire to secure by Letters Patent, is—

1. A trolley-controller comprising a support, an extensible spring having its lower end fixed to the support from endwise movement and its other end movable vertically, means connected to the free end of the spring for extending and tensioning the same vertically, a catch mounted on said free end of the spring for interlocking with a portion of the support and holding the spring tensioned, and an operating-cord or its equivalent connected to the catch whereby the sudden tensioning of the cord operates to release the catch and spring for the purpose described. 15
2. A trolley-controller comprising a support, an extensible spring having its lower end swivel-connected to the support and fixed from endwise movement and its other end movable, means connected to the upper end 20 of the spring for tensioning the same, a catch mounted on the free end of the spring and adapted to interlock with the support for holding the spring tensioned, and an operating-cord or its equivalent connected to the 25 catch and to the trolley-arm whereby the sudden tensioning of the cord operates to release the catch and spring for the purpose specified. 30
3. A trolley-controller comprising a support, a spring having its lower end fixed from endwise movement and its other end adapted to be extended or tensioned vertically, means for extending the spring, a catch mounted on the free end of the spring and arranged to automatically interlock with a portion of the 35 support when the spring is tensioned, a sheave connected to the catch, and a cord connected to the support and sheave and adapted to be connected to the trolley-arm, said catch and spring being released by the sudden tensioning of the cord for the purpose set forth. 40

4. The combination with a support, a trolley-arm-operating cord or its equivalent, and a take-up device for the cord, of a spring fixed at one end from endwise movement and having 45 its other end extensible vertically and provided with a spring-actuated catch for engaging the support and holding the spring tensioned, said catch being released by the cord as and for the purpose specified, and means for extending or tensioning the former spring. 50

5. The combination with a support and an automatic take-up device for the trolley-arm-operating cord, a spring having one end swiv- 60 eled on the support and its other end extensible and provided with independent sheaves one being engaged by the trolley-arm-operating cord, a flexible member connected to the other sheave for tensioning the spring, and a 65 catch connected to the former sheave for engaging the support and holding the spring in its tensioned position, said former sheave be-

ing movable by the cord for releasing the catch and spring.

6. The combination with a support, a trolley-arm-operating cord or its equivalent, and a spring having one end fixed from endwise movement and its other end extensible and provided with a sheave, a take-up drum mounted on the support, a flexible member connected to the take-up and to the sheave whereby the spring may be tensioned, and a catch for holding the spring tensioned, said catch being connected to the operating-cord of the trolley-arm for the purpose specified. 70

7. The combination with a support having its opposite walls provided with bearings, one being adjustable toward and away from the other, a circular toothed rack concentric with one of the bearings, a take-up drum mounted 75 on the bearings and provided with a centrifugally-actuated pawl adapted to engage the teeth of the rack as described, and a trolley-arm-operating cord connected to the drum. 80

8. The combination with a support and a take-up device for the trolley-arm-operating cord, a swivel connected to the support, a spring having its lower end fixed from endwise movement to the swivel, and its upper end extensible and provided with a catch for 90 engaging the support and holding the spring tensioned, a second take-up drum between the spring and former drum, and flexible means connected to the second drum and to the upper end of the spring for tensioning the spring. 95

9. In a trolley-controller, the combination with a support having separated bearings, one being adjustable toward and away from the other, a spring-actuated take-up drum revolvably mounted on said bearings, and a trolley-arm-operating cord connected to the drum. 100

10. In a trolley-controller, the combination of a support having separated walls one being provided with a ball-bearing and the other being removable and provided with an adjustable cone-bearing, and a revoluble spring-actuated take-up drum mounted on the bearings and having one end of a trolley-arm-operating cord connected thereto. 110

11. The combination with an inclosing case 115 or frame having inner engaging shoulders, an extensible spring within the frame and having its lower end fixed thereto from endwise movement and its upper end provided with a catch adapted to engage the shoulders when the 120 spring is extended, means connected to the upper end of the spring for tensioning the same, and a take-up device supported in the frame and connected to the operating-cord of the trolley-arm, said cord being connected to the catch for effecting the release of the spring and the spring serving to draw the cord downwardly. 125

12. In a trolley-controller the combination of an inclosing case or frame having an engaging shoulder, an extensible spring having one end fixed from endwise movement to a swivel and its other end movable and provided with a catch for engaging said shoulder 130

and holding the spring tensioned, independent sheaves connected to the upper end of the spring and movable therewith, one of the sheaves being movable vertically independently of the spring, independent take-up drums mounted on the frame, a cord or its equivalent engaged with the lower face of the sheave connected to the catch and having one end connected to one of the drums and its other end adapted to be connected to the trolley-arm, and a second cord or its equivalent

engaged with the lower face of the other sheave and having one end connected to the other drum and its other end provided with a handpiece for the purpose set forth. ¹⁵

In witness whereof I have hereunto set my hand this 14th day of March, 1901.
